(57) **CLAIM**

The ornamental design for an earphone enhancer, as shown and described.

DESCRIPTION

FIG. 1 is a front view of an earphone enhancer showing our new design, a left-handed version being illustrated in FIGS. 1-6;

FIG. 2 is a rear view thereof;

FIG. 3 is a side elevation view of one side thereof;

FIG. 4 is a side elevation view of the opposite side thereof;

FIG. 5 is a top view thereof;

FIG. 6 is a bottom view thereof;

FIG. 7 is a front view of a right-handed version of the earphone enhancer showing our new design;

FIG. 8 is a rear view thereof;

FIG. 9 is a side elevation view of one side thereof;

FIG. 10 is a side elevation view of the opposite side thereof;

FIG. 11 is a top view thereof; and,

FIG. 12 is a bottom view thereof.

The broken lines depict environment that forms no part of the claimed design.
